LOCK BOLT

Seth C. George, Los Angeles, Calif.

Application August 9, 1944, Serial No. 548,715

3 Claims.

(Cl. 151—2)

1

The present invention relates to lock nuts and bolts, and more particularly to a cooperating nut and captive lock washer, and a captive bolt adapted to be positioned against turning in its hole.

An object of the invention is to provide a headless bolt with threaded means on each end for carrying a turnable nut.

Another object is to provide a threaded bolt with means for holding it captive against turning in its hole.

A further object is to provide a nut with means on its engaging face for holding a standard lock washer against turning relative thereto.

A still further object is to provide a standard lock washer of relatively hard material in combination with a cooperating washer of softer material surrounding it and having means thereon preventing relative movement of said washers.

Yet another object is to provide a watertight seal between a headless bolt and a head nut therefor.

Finally, an object is to combine all or part of these features into a method and means for bolting anything together in a positive permanent manner which will defy vibration to loosen it prematurely, which will prevent the bolt turning in its hole automatically while applying the holding nuts, and which will provide a watertight seal from at least one side.

All these and other objects, as suggested herebelow, are attained by the method and means now to be described, and illustrated in the accompanying drawing, in which,

Figure 1 is a side elevational view of a preferred embodiment of the headless bolt of this invention, showing a means for locking same against turning in its hole.

Figure 2 is a cross-sectional view of a bolt showing an alternate means of providing the captive or non-turning feature thereto, as by swedging a continuously-threaded rod.

Figure 3 is a side-elevational view, and Figure 4 is a bottom plan view of one form of nut, showing a means on its base for holding captive against turning a standard lock washer.

Figure 5 is a side-elevational view of another form of nut equipped with a recess for a standard lock washer and means for holding it captive relative thereto.

Figure 6 is a bottom plan view of the nut of Figure 5.

Figure 7 is a side-elevational view, and Figure 8 is a top plan view, of the soft-metal washer in combination with a standard lock washer for

2

preventing turning of the latter relative thereto, and also, perhaps, as a water-tight sealing aid.

Figure 9 is a side-elevational assembly view, partly in phantom, of the completely assembled bolt-nut-and-washers combination as applied, for instance, in permanently holding overlapping ship's plates in a water-tight non-loosening manner.

Like numerals refer to like parts throughout the several views.

The captive bolt of this invention as shown in Figure 1, may consist of a threaded bolt 10 with a non-threaded portion 12 intermediate its ends and remote from one end a distance substantially equal to the thickness of the nut to be applied thereto to form a tightening element or head thereof. Extending outwardly from portion 12 are an equi-spaced plurality of bolt-holding ridges 13, preferably triangular in cross-

section, and tapering downwardly and inwardly toward the bolt's center to disappear completely at that near edge, as clearly disclosed. These tapering ridges permit the bolt to be held captive in its hole, for when the bolt is tapped on its end with a hammer, ridges 13 cut slight keyways in the hole's wall and at the same time swedge themselves into tight binding engagement therewith to completely and jammingly fit the somewhat larger hole, to thus prevent turning until later tapped out from the other direction when removing same, which operation will be aided by their taper. The head end of the bolt at least, or both ends as here shown, is slightly rounded over the end portion of the bolt as at 15a to aid the watertight seal.

An alternative means of forming this captive feature is shown in Figure 2, wherein the threaded portion 10 is first made continuous, after which the ridges 14, shown as shaped as 13 in Figure 1, are swedged outwardly by utilizing the threaded stock itself and flattening it out somewhat as shown in the portion between the ridges.

The nut shown in Figures 3 and 4, and which may be used for the bolt head, may be hexagonal-shaped near its base, as at 15, with a rounded upper portion as shown, and the usual threaded bore 16 to engage the threads of bolt 10. Radial spaced grooves 17 are formed in the base as shown to permit the resilient locking end of the standard lock washer to be caught therein and so held against relative movement therewith. Thereafter the nut is brought up tight against the work (for instance, the ship's plates 25—26) by taking up on the other or tightening nut. The nut shown in Figure 5, and which may be

the tightening nut, is similar in shape to that of Figure 3, except that it has a washer-like base portion 23 projecting from the hexagonal portion 21, through both portions of which threaded hole 22 extends. In the base portion 23 a circular recess 24 is formed, of a diameter and depth to admit a standard lock washer 20, and completely enclose it. Washer-holding grooves are formed in the base of recess 24 similar to those at 17 in Figure 4. Also the peripheral edge of this recess may be tapered inwardly and of a diameter to snugly fit the peripheral edge of the lock washer to hold it tightly in place when the parts are screwed together.

When the washer shown at 18 is used it may have a number of prongs 19 formed thereon and directed inwardly to engage the bolt 10 and maintain the washer concentric therewith, thereby permitting the same to be made much narrower than would be the case if made in the customary way and making the saving of material very considerable.

It will be understood, of course, that the nut types described above may be reversed on the bolt ends, or either type may be used on both ends.

Some such material as a rust-proof lacquer may be applied to the bolt and nuts, including their threads, which will make the joint between the two water-tight as well.

Great economies are effected by use of this headless bolt stem, with nuts, permitting carrying less parts in stock since different bolt lengths are obtainable by cutting off from lengths of threaded bolt stock. And different type heads are also obtainable by simply applying different type head nuts etc. Kinking or slipping of the lock washer is prevented by this construction, and it is more easily applied because held captive in the assembly. Taking up on nuts at both ends results in more uniform gripping action, and double tension, which absorbs all shrinkage of material and prevents chattering or coming loose. The ideal combination of bolt stock and length, head nut and fastening nut, and washers, may be readily assembled for any particular job, with minimum purchase of parts.

Having now described the invention, what I claim as new and desire to secure by Letters Patent, is:

1. In combination, a pair of juxtaposed plates having axially aligned holes therethrough, a headless bolt threaded at each end positioned in the holes and provided with means on its central portion to seat in the hole wall to prevent its turning when nuts are screwed thereon and comprising ridges tapering centrally from one end so that they may be driven into fixed engagement with the hole wall, a nut screwed on each end of the bolt, and means operative to prevent unintentional displacement of the nuts

on the bolt said latter means comprising a flat washer disposed between each plate and its adjacent nut and having substantially flat, inwardly extending, prong means therein, and further having a split, lock washer seated within said flat washer with its split end located adjacent an edge of said prong means, the combined thickness of said prong means and lock washer not exceeding that of the encircling flat washer.

2. A composite washer assembly comprising a flat washer having substantially flat, inwardly extending prong means therein and having a split, lock washer seated within said flat washer with its split end located adjacent an edge of said prong means, the combined thickness of said lock washer and prong means not exceeding that of the encircling flat washer, whereby said composite washer may be disposed on a shaft between a flat surface and a mounted nut to completely seal the space therebetween against entrance of moisture.

3. In combination, a pair of juxtaposed plates having axially aligned holes therethrough, a bolt positioned in the holes, a radially enlarged tightening element disposed on each end of said bolt, at least one of said elements being threadedly mounted thereon, a flat washer disposed between each plate and its adjacent tightening element and having substantially flat, inwardly extending, prong means therein, and a split, lock washer seated within said flat washer with its split end located adjacent an edge of said prong means, the combined thickness of said prong means and lock washer not exceeding that of the encircling flat washer, and the abutting face of each of said tightening elements extending circumferentially beyond the adjacent aperture of the flat washer so as to seal same against passage of moisture.

SETH C. GEORGE.
